UNITED STATES PATENT OFFICE.

MAX MATTES, OF NEW YORK, N. Y.

DESIGN FOR A CAP.

No. 39,202.

Specification for Design.

Patented March 17, 1908.

Application filed December 20, 1907. Serial No. 407,430. Term of patent 3½ years.

To all whom it may concern:

Be it known that I, MAX MATTES, a citizen of the United States, residing at the city of New York, borough of Manhattan, in the county and State of New York, have invented a new, original, and ornamental Design for Caps, of which the following is a specification, reference being had to the accompanying drawing, forming part thereof.

The figure is a view of a cap partially in perspective showing the design.

I claim:

The ornamental design for caps, as shown.

MAX MATTES.
